ELEVATOR SWITCH

Felice Petrullo, Jersey City, N. J., assignor to
Industrial Patents Corporation, Chicago, Ill., a
corporation of Delaware

Application February 17, 1945, Serial No. 578,373

1 Claim. (Cl. 171—97)

1 This invention relates to a switch and more particularly to a tamper proof switch especially suitable for use in elevator controls.

In modern elevator controls, interlocking switches actuated by the doors of the elevator are usually employed to disable the elevator control circuit to prevent movement of the elevator when any door is open. The switches referred to are provided for safety purposes to prevent injury to elevator operators, passengers, etc. Particularly in the case of freight elevators, the operators thereof, in disregard of safety regulations, frequently tamper with the safety switches in order to permit operation of the elevator with the doors open. The present invention provides a switch which is extremely difficult to actuate with the door open without destruction of the lock or seal of the switch casing or the disabling of the elevator control circuit. Insertion of a member of insulating material into the switch actuator aperture will not render the elevator control switch operative and insertion of an electrically conducting member will disable the elevator control circuit until repaired by an authorized person.

It is therefore an object of the invention to provide a substantially tamper proof safety switch for elevator doors and similar structures.

Another object of the invention is to provide an improved elevator safety switch which is difficult to actuate to enable the elevator to be moved except by the actuator operated by closing of the elevator doors.

A further object of the invention is to provide a safety switch for elevator doors which either is not actuated or which completely disables the elevator control circuit when an attempt is made to introduce an incorrect actuator into the actuator aperture of the switch.

Other objects and advantages of the invention will become apparent from the following description of preferred embodiments of the invention shown in the attached drawings of which

Figure 1 is a vertical section through a switch of the present invention showing an actuator therefor;

Figure 2 is a vertical section taken on the line 2—2 of Figure 1;

Figure 3 is a fragmentary section showing a modification of a portion of the switch of Figure 1;

Figure 4 illustrates one type of circuit in which the present switch can be employed; and

Figure 5 illustrates a modified circuit in which the switch of the present invention can be employed.

Referring to the drawings, the switch of Figures 1 and 2 may include a casing 10 provided with a cover 11 which may be secured to the casing 10 in any desired manner so as to be capa-

ble of being sealed or locked to the casing 10, for example, by a pin 12 and a seal 13. The casing 10 may be provided with an elongated tubular member 14 projecting from one side thereof to form a guide opening 16 for a switch actuator 17. The tubular member 14 may be welded or otherwise suitably secured to the casing 10 to prevent removal thereof from the exterior of the casing.

10 The casing 10 may contain a pair of spring contact members 18 and 19 suitably secured, for example, by rivets 20 to insulating members 21 and 22 secured to the top and bottom walls of the casing, for example, by rivets 23. The contact members have their contact portions in alignment with the actuator aperture 16 for contact with the actuator 17 when said actuator is inserted through the aperture 16. The casing may also contain a fuse 24 supported in suitable fuse clips 26 and 27 in turn supported upon a block of insulating material 28 secured to the base of the casing. Conductors 29 and 31, for example, the conductors of a standard BX cable 32 may enter the casing through a cable connector 33. The spring contacts 18 and 19 may be connected in a series circuit with the fuse 24 and the conductors 29 and 31, a short conductor 29a being employed to connect the fuse clip 27 with the spring contact 19.

30 The spring contacts 18 and 19 normally occupy the positions shown in Figure 1 so that the circuit through the switch box is open, the circuit being closed between the contacts 18 and 19 upon insertion of the actuator 17. This actuator may include a body member 34 of either conducting or non-conducting material although the body member is preferably made of a section of small iron pipe. The inner end portion 36 of the actuator 17 is, however, constructed of insulating material provided with a metallic band 39 intermediate its ends. The insulating material 36 may be secured to the body portion 34 of the actuator in any desired manner (not shown). The actuator 17 may also be provided with a stop member 41 so that movement of the actuator to the right in Figure 1, until the stop member 41 contacts the guide member 14, positions the conducting band 39 of the actuator between the spring contacts 18 and 19 to complete the circuit through the switch. It will be apparent that insertion of a member of insulating material such as a rod of wood into the switch can not complete a circuit through the switch and that insertion of a member of electrically conducting material such as a rod of metal into the switch will produce an electrical connection between the contacts 18 and 19 and the switch casing.

55 For purposes of illustration, a circuit is shown in Figure 4 which can be employed with the switch of Figures 1 and 2. Two switches each

including spring contacts 18 and 19 are shown in Figure 4, each pair of contacts being associated with a fuse 24. The contacts of the two switches and the fuses 24 may be connected in series with a source of voltage 42. When a circuit is completed through both sets of contacts 18 and 19, the elevator control circuit including the conductors 44 is closed to enable movement of the elevator. It will be apparent that as many switches as there are doors on the particular elevator may be employed in the series circuit. It will be further apparent that an actuator such as the actuator 17 shown in Figure 1 must be employed to complete the circuit between the contacts 18 and 19. An insulating member will not close this circuit. Furthermore, the guide member 14 for the actuator is shown as being connected to ground and one terminal of the source 42 is also shown as being connected to ground at 46. Insertion of a conducting member through the guide member 14 must contact both contacts 18 and 19 to complete the circuit and upon engaging contact 19 and the guide member 14, a short circuit through a fuse 24 will be produced causing blowing thereof so as to completely disable the control circuit preventing operation of the elevator. Movement of the elevator can not then be accomplished until the blown fuse 24 has been replaced and all doors closed.

In cases where it is undesirable to ground one side of the source 42 or to have the casing 10 of the switch electrically connected to the source, the actuator guide structure of Figure 3 may be employed. In this figure, a conducting inner sleeve 47 is shown as being insulated from an outer sleeve 48 by means of an insulating sleeve 49 and an insulating washer 51. The conducting sleeve 47 may have a portion 52 projecting internally of the casing 10 for connection to one side of the source of electric voltage. The structure of Figure 3 can be advantageously employed in the circuit of Figure 5 in which the contacts 18 and 19 of a plurality of switches are each in a series circuit including a fuse 24 and a relay 53, these series circuits being connected in parallel across a source 42 of voltage. The conducting sleeves 47 are connected to one side of the source 42 so that insertion of a conducting member through the sleeve 47 will short circuit contact 19 through its associated fuse 24, thus disabling the circuit so that the associated relay 53 can not be closed. Since closure of both relays 53 is necessary to close the control circuit, including the conductors 54, the elevator can not be operated until the blown fuse 24 is replaced.

It will be apparent that the grounded sleeve 14 of the switch of Figure 1 can be employed in the circuit of Figure 5 by connecting the casing 10 in the same manner as the sleeve 47 of Figure 5 is shown connected and that the insulating guide sleeve of Figure 3 can be employed in the circuit of Figure 4 by connecting the same to ground. The specific structures shown in Figures 1 to 3 are by way of example as various other arrangements of contacts and actuator guides can be employed. By employing an elongated conducting guide member for the actuator and arranging the contacts to close the circuit only when a conducting portion of the actuator, insulated from the main body of the actuator, is between the contacts, it is extremely difficult to actuate the switch with any instrumentality other than a

properly designed actuator, not ordinarily available to elevator operators and other employees using the elevators. It is, therefore, extremely difficult for such employees to condition the control circuit for elevator movement when the doors of the elevator are open. Also the circuits of Figures 4 and 5 are merely illustrative as the switch is capable of being employed in any one of a large number of different circuits including control circuits for structures other than elevators. That is to say, the switch has utility whenever it is desired to prevent closing of a circuit except by a properly designed actuator.

While I have disclosed the preferred embodiments of my invention, it is understood that the details thereof may be varied within the scope of the following claim.

I claim:

20 A safety switch for use in association with a system of elevator doors and the like comprising a sealed casing, a pair of spaced contacts supported within said casing, an actuator to complete a circuit through said contacts, an electrically conductive actuator guide member secured to said casing and having an elongated bore extending into said casing to direct the actuator into position between the contacts, said actuator having an insulating portion normally in contact with said guide member and an electrically conductive tip to cooperate with said contacts, said guide element and said contacts being connected through a source of electrical energy, said circuit being arranged so that when completed through the guide member a flow of current may take 25 place through at least one of said contacts, means electrically connected with the guide to render the circuit permanently inoperative when the circuit is completed through the guide, said actuator being moved by the elevator door or the like 30 to render a circuit through the contacts operative when the door or the like is closed and to render said circuit through the contacts inoperative when the door or the like is open, and said guide-member circuit normally being maintained open 35 by reason of its contact with the insulated portion of the actuator but the guide member circuit functioning to render the entire circuit permanently inoperative when a substitute electrically conductive actuator is substituted for the 40 actuator that cooperates with the door or the like 45 whereby the circuit through the guide member is completed.

FELICE PETRULLO.
